CLAIM

The ornamental design for a combined brush and scraper to be used in cleaning windshields, substantially as shown and described.

DESCRIPTION

FIG. 1 is a bottom perspective view of a combined brush and scraper to be used in cleaning windshields, showing our new design;

FIG. 2 is an elevational view of the side opposite that shown in FIG. 1;

FIG. 3 is a top plan view thereof;

FIG. 4 is a bottom perspective view of a second embodiment of a combined brush and scraper to be used in cleaning windshields;

FIG. 5 is an elevational view of the side opposite that shown in FIG. 4;

FIG. 6 is a top plan view thereof.
